UNITED STATES PATENT OFFICE.

JAMES HUNTER, OF CAMDEN, NEW JERSEY.

EXPLOSIVE PROJECTILE.

SPECIFICATION forming part of Letters Patent No. 325,608, dated September 1, 1885.

Application filed July 17, 1884. (No model.)

To all whom it may concern:

Be it known that I, JAMES HUNTER, a subject of the Queen of Great Britain and Ireland, and a resident of Camden, New Jersey, 5 have invented certain Improvements in Projectiles, of which the following is a specification.

The object of my invention is to effect the throwing of dynamite shells or other explosive projectiles without the use of a special gun, and this object I attain in the manner hereinafter set forth.

Projectiles containing dynamite, nitro-glycerine, and other powerful explosives, especially 15 such as are intended to be exploded by concussion, cannot be fired from ordinary guns on account of the violent action upon the projectile caused by the firing of the charge of the gun; hence elaborate and expensive special guns have been devised for the purpose of throwing such projectiles. The use of a special gun I dispense with by connecting the explosive projectile by any suitable medium, such as a cord or chain, to the shot of an ordinary gun, so that when the shot is fired it will 25 carry the explosive projectile with it, the flexible connection being preferably provided with a coiled spring or other elastic portion, so as to lessen the shock upon said projectile 30 and lessen the risk of premature explosion of the same.

The gun may be an ordinary field-gun, siege-gun, mortar, or even a musket or rifle, having

a small explosive projectile connected by a flexible and elastic medium to the bullet of 35 the regular cartridge; or the projectile may be connected to the head of a rocket when this is more available than a gun.

In the accompanying drawing, which shows one way of carrying out my invention, A 40 represents the gun, b the shot of the same, and a an explosive bomb connected to the shot by a cord, d, and coiled spring f.

The projectile may be constructed to explode by concussion on striking the object 45 aimed at, or it may be exploded by a time-fuse in the same manner as an ordinary shell, and where such fuse is used it may be automatically ignited on the discharge of the shell by coating it with fulminate or igniting composition held in contact with an abrading surface, across which the fulminate is drawn, so as to be ignited when the shell commences its 50 flight.

I claim as my invention—

A projectile consisting of a shot adapted 55 to a gun, an explosive bomb, and a flexible and elastic connection between the said shot and bomb, as set forth.

In testimony whereof I have signed my 60 name to this specification in the presence of two subscribing witnesses.

JAMES HUNTER.
